SUGAR PROCESS.

1,352,084.

Specification of Letters Patent.

Patented Sept. 7, 1920.

Application filed December 27, 1915. Serial No. 68,636.

To all whom it may concern:

Be it known that we, RUDOLPH E. POSPISIL, a citizen of the United States, and resident of Chippewa Falls, in the county of Chippewa 5 and State of Wisconsin, and EDMUND KUREK, a citizen of the United States, and resident of Madison, in the county of Dane and State of Wisconsin, have invented new 10 and useful Improvements in Sugar Processes, of which the following is a description, reference being had to the accompanying drawings, which are a part of this specification.

This invention has for its object to 15 prove upon the sugar process covered by United States Letters Patent No. 1,028,272, granted June 4, 1912, to Rudolph E. Pospisil, and effect a greater recovery of granulated white sugar of high purity.

20 The present invention relates to a large extent to the purifying of the massecuite by injecting water during the treatment in the vacuum pan and also during crystallization while the crystallizers are in motion in order 25 to extract the sugar from the molasses.

With the above and other objects in view the invention consists in the sugar process as herein claimed and all equivalents.

Reference will be made to the accompanying 30 drawing which is a diagram of the process of this invention representing the several strikes by lines connecting the various mechanisms in the order that the juice in its various stages travels through them.

35 In conducting the sugar making process of this invention raw juice is first boiled in vacuum pan 1, where it is treated with injections of water while its temperature is being raised so as to volatilize or expel such 40 impurities as ammonia, ammonium carbonate, acetate, and to decompose other nitrogenous matters, raising the purity of the massecuite in the vacuum pan.

45 This treatment is repeated many times until the massecuite is finished, when it is dropped into a mixer 2 from which it passes to a centrifugal separator 3. The sugar from the centrifugal separator 3, testing 98-99 purity, is melted in melter 4 and after 50 being treated and filtered as usual is passed to a second vacuum pan 5 where it is boiled again to massecuite and dropped into mixer 6 and then into centrifugal separator 7. Here the sugar crystals are separated from

the syrup as pure, white granulated sugar of 55 the purity of from 99-99.5 completing the first strike, while the syrup and the wash water continue through the process, the wash water being returned to the vacuum pan 5 as part of the same strike, while the syrup 60 from centrifugal 7 is delivered to vacuum pan 1^a, where it meets the raw syrup from centrifugal separator 3 to begin the second strike.

In the second strike these syrups from the 65 separator 3 and centrifugal 7 are boiled in vacuum pan 1^a to form crystals and as soon as the crystals are formed the water action or injection treatment is repeatedly used the same as with the raw juice in the first strike. 70 When the massecuite from the second raw syrup is finished it is dropped into the mixer 2^a and then into centrifugal separator 3^a and the sugar from centrifugal separator 3^a passes to the melter 4^a where it is melted. 75 The juice or liquid from melter 4^a after being treated and filtered as usual is passed to vacuum pan 5^a where it is boiled to a massecuite and is dropped into mixer 6^a and centrifugal separator 7^a where the sugar 80 crystals are separated and washed with water and dried to complete the second strike of white, granulated sugar of the same quality as the first strike. A part of the raw syrup of the second strike from centrifugal separator 3^a and all of the white sugar syrup of the second strike from centrifugal separator 7^a are drawn together into 85 the vacuum pan 1^b to begin the third strike.

These two mixed syrups from separators 90 3^a and 7^a respectively are boiled in vacuum pan 1^b to form crystals and as soon as the crystals are formed the water injection takes place again and is repeated until finished as previously mentioned. As soon as the massecuite is finished it is dropped into crystallizers 8^b where it begins to thicken, and thereupon the water injection is used during the time the crystallizers are in motion and is continued as long as necessary to prohibit 100 or stop the crystals from taking on the impurities. When this massecuite is finished it is dropped into mixer 2^b and from mixer 2^b to centrifugal separator 3^b. The crystals in centrifugal separator 3^b are separated 105 from the residue or molasses formed thereon and are passed into melter 4^b where they are melted and mixed with high raw juice. This

mixture in melter 4^b is then treated, filtered and passed into vacuum pan 5^b and through mixer 6^b and centrifugal separator 7^b where high quality granulated sugar is obtained to 5 complete the third strike.

To begin the fourth strike for the production of a dark sugar for addition to the previous strikes the remainder of the syrup from the centrifugal separator 3^a of the 10 second strike and also the molasses of centrifugal separator 3^b of the third strike are drawn together in vacuum pan 1^c and boiled down to a thickness or string which is known by the name of "blank." The water 15 action or injection is applied as before during the boiling in vacuum pan 1^c for the fourth strike to volatilize and expel the impurities. When this is finished it is dropped into the crystallizers 8^c and water 20 injection is again used while the crystallizers are in motion. The finished massecuite is dropped into mixer 2^c and centrifugal separator 3^c where a dark colored sugar is separated which is melted in the melter 4 to 25 complete the fourth strike. A part of this dark sugar from melter 4^c is mixed with the raw juice in vacuum pan 1 of the first strike to be boiled over again while the other part of the dark sugar from melter 4^c is mixed with 30 the second raw syrup in vacuum pan 1^a in the second strike to be boiled over again. The syrup from centrifugal separator 3^c is being constantly used to raise the purity 35 of the molasses. The syrup from the centrifugal separator 3^a of the second strike and the molasses from centrifugal separator 3^b of the third strike are being boiled over many times until all of the sugar is extracted, all of the by-products or dark sugar 40 being used for mixing with high and low raw syrups and boiled over again.

By means of this process all of the sugar from the molasses is extracted as a pure high quality granulated white sugar.

45 What we claim as new and desire to secure by Letters Patent is:

1. The process of making white granulated sugar which consists in treating the raw juice to recover the first strike of sugar 50 therefrom, boiling in a vacuum pan the syrups from the first strike and a part of the dark sugar from the blank of a later strike, subjecting the same to water injections and raising the temperature to remove

impurities, separating the crystals from the 55 syrup, melting them and boiling the melted crystals in a vacuum pan to a massecuite and recovering the crystals therefrom.

2. The process of producing white granulated sugar which consists in obtaining a 60 first and second strike of sugar, boiling in a vacuum pan a part of the raw syrup from the second strike and all of the white sugar syrup from the second strike to form crystals, injecting water in the vacuum pan as 65 soon as the crystals are formed to remove impurities therefrom, separating the crystals from the residue, and mixing these crystals in a melter with raw juice, boiling the mixture from the melter in a vacuum pan and 70 recovering the sugar therefrom.

3. The process of producing granulated white sugar which consists in obtaining three strikes of sugar, boiling in a vacuum 75 pan the syrup from the second strike and the molasses from the third strike to form blank, injecting water in the blank during the boiling so as to remove impurities therefrom, treating the massecuite in crystallizers with water injections during the action of 80 the crystallizers, recovering dark sugar crystals and melting them and returning a part to the raw syrup of the first strike and a part to the raw syrup of the second strike to be boiled over in the vacuum pan there- 85 with.

4. The process of making white granulated sugar which consists in treating the raw juice to recover the first strike of sugar 90 therefrom, boiling in a vacuum pan the raw syrup from the first strike and the white syrup from the first strike, subjecting the same to water injections and raising the temperatures to remove impurities, separating the crystals from the syrup, melting 95 them, boiling the melted crystals in a vacuum pan to a massecuite, and recovering the crystals therefrom.

In testimony whereof, we affix our signatures, in presence of two witnesses.
